UNITED STATES PATENT OFFICE.

JONATHAN D. MAXWELL, OF TARRYTOWN, NEW YORK.

EXHAUST AND SIGNAL CONTROL.

No. 896,455.

Specification of Letters Patent.

Patented Aug. 18, 1908.

Application filed August 23, 1907. Serial No. 389,793.

To all whom it may concern:

Be it known that I, JONATHAN D. MAXWELL, a citizen of the United States of America, residing at Tarrytown, in the county of Westchester and State of New York, have invented certain new and useful Improvements in Exhaust and Signal Control, of which the following is a specification, reference being had therein to the accompanying drawings.

In automobiles, motor boats, and the like, the motor exhaust is frequently used to operate a signal whistle, but the fluctuations in pressure cause unpleasant pulsations and variations in the pitch and intensity of the sound. It is also customary to muffle the exhaust when desired.

This invention relates to a combined exhaust and signal controlling means, where- 20 by the intermittent exhaust pressure may be made to produce a sustained tone in a suitable whistle-bell or horn, and whereby the exhaust may be muffled, allowed to directly escape, or be made to operate the 25 whistle.

The invention consists in the matters hereinafter set forth, and more particularly pointed out in the appended claims.

In the drawings, Figure 1 is a view in longitudinal section of an exhaust and signal controlling mechanism which embodies the features of the invention. Fig. 2 is a view in side elevation of the device.

Referring to the drawings, the device, in 35 its preferred form of construction, consists of a central pipe 1, exteriorly screw-threaded at one end for attachment to the exhaust of an internal combustion motor, and at the other for a controlling valve casing 2 which is counterbored and fitted to engage the pipe.

The body of the pipe is perforated, the orifices having a combined area slightly less than the cross-sectional area of the pipe, so that the exhaust is slightly restricted accord- 45 ing to established muffler construction.

An outer closed cylindrical shell 4 and an intermediate cylinder whose body wall 5 is perforate, are concentrically secured on the pipe, their outer end plates 7 and 8 being clamped between lock nuts 9 on the inlet end of the pipe. An inner head plate 10 of the intermediate cylinder is secured against a circular muffler head 11, integral with the valve casing 2 by a nut 12. The correspond- 55 ing end of the shell is closed by the muffler head itself, the shell being secured to a per-

ipheral flange 13 thereon by rivets 14 or the like.

While the cylinder and shell may be made in any approved manner, the preferred form 60 of construction is that shown, wherein the end plates 7, 8 and 10 of sheet metal, present integral, inrolled, rounded peripheral flanges 35 which are retained in corresponding circumferential grooves 15, struck up or rolled 65 in the end portions of the sheet metal cylinder bodies, thus forming a solderless lap joint which retains the parts while allowing for their unequal expansion.

The valve casing 2 is suitably designed and 70 counterbored for a hollow cylindrical closure 16 with closed ends, secured transversely to the muffler axis by a stud 17 integrally formed on its lower end, extending through the casing, and a spring 18 encircling the 75 stud, in compression between the casing and a washer and cotter pin 19 on the stud. A lever 20 suitably secured as by a pin 21 to a central boss 22 on the head of the closure, rotates it, a stop pin 23 traveling in a gain 80 or notch 24 in the casing or other like means limiting its movement.

A direct exhaust passage 34 leads from the pipe 1 through the muffler head into the interior of the casing and may be thrown into 85 communication with a common discharge opening 25 by a pair of apertures 26 and 27 in the cylindrical closure wall, which are so disposed that they may be brought simultaneously into register with the passage and 90 opening by rotation of the closure.

A muffler exhaust duct 28 of less area than the orifices in the intermediate cylinder, leads through the muffler head from the outer shell diagonally into the interior of the 95 casing between the direct exhaust and the discharge, and may be brought into communication with the discharge opening 25 by the aperture 26 which is large enough to simultaneously register with or uncover both. 100 Or the duct may be connected with a diametrically opposite blast duct 29 through both apertures 26 and 27. A sounding bell 30 either of a horn or a whistle, is mounted on the outer end of the casing in axial alignment with the muffler by a central stud 31 on which it has the usual longitudinal screw-threaded adjustment. The discharge from the blast duct 29 is operatively directed by a suitable annular casing rim 32 and disk 111 33 against the whistle bell.

The three-way valve construction enables

the operator either to cut out the muffler or else use the muffler exhaust to sound the whistle. In so doing, the muffler itself owing to the restriction of the exhaust becomes a pressure chamber whereby a constant pressure is maintained and the pulsations of the exhaust are so modified that the discharge therefrom is substantially constant, and an even sustained tone in the whistle is obtained. Another feature of the invention is the compactness of the design, which adapts it especially for automobile and small boat use. Still another advantage is the avoidance of extra parts, the one valve controlling the exhaust in the usual way, and likewise operating the signal, while all outside pipe connections and auxiliary pressure tanks are avoided.

Obviously, the design and details of construction may be varied without departing from the spirit of the invention, and I do not care to limit myself to any particular form of construction or arrangement of parts except as required by the scope of the appended claims.

What I claim as my invention is:—

1. An exhaust and signal control, comprising a muffler having a direct and an indirect outlet adapted to maintain a constant back pressure in its contents, when discharging through the indirect outlet, a signaling means and means adapted to operatively connect the indirect outlet and signaling means, and to close either the direct or indirect outlet independently of the signal.

2. An exhaust and signal control, comprising a muffler having a direct and indirect outlet adapted to maintain a constant back pressure in its contents when discharging through the indirect outlet, signaling means, and means integral with the muffler and signaling means adapted to operatively connect the indirect outlet and signaling means, and to open either the direct or indirect outlet independently of the signaling means.

3. An exhaust and signal control, comprising a muffler having a direct and indirect outlet adapted to maintain a constant back pressure in its contents when discharging through the indirect outlet, signaling means adapted to be operated by the pressure of the muffler contents, and means adapted to operatively connect the indirect outlet and the signaling means, and also to open either the direct or indirect outlet.

4. An exhaust and signal control, comprising a muffler, a direct outlet therefrom, a restricted indirect outlet therein, a signaling means, and controlling means adapted to simultaneously close the direct outlet and operatively connect the indirect outlet and signaling means and also to open either the direct or indirect outlet independently of the signaling means.

5. An exhaust and signal control comprising

ing a combined exhaust muffler and pressure chamber, a direct exhaust passage therethrough, a restricted outlet therefrom, signaling means, and controlling means adapted to simultaneously close the passage and 70 to operatively connect the outlet and signaling means and to close either the passage or the outlet independently of the signaling means.

6. An exhaust signal and control, comprising a combined exhaust muffler and pressure chamber, a direct exhaust passage therethrough, a restricted outlet therefrom, signaling means, and controlling means integral with the muffler chamber and the signaling 80 means, adapted to simultaneously close the passage and operatively connect the outlet and signal and to close either the exhaust passage or the outlet independently of the signaling means.

7. An exhaust and signal control, comprising an exhaust muffler, a muffler head having a valve casing and blast signal integral thereon, a direct exhaust passage through the muffler head and casing, an indirect exhaust outlet through the head and casing, a signal blast duct in the casing, and a closure, adapted to connect the outlet and blast duct, and simultaneously close the exhaust passage, and to also alternately open 95 the passage and outlet.

8. An exhaust and signal control, comprising an exhaust muffler having a direct exhaust passage therethrough, an indirect exhaust passage terminating in a single restricted outlet, a blast signal, and controlling means adapted to operatively connect the outlet and signal and simultaneously therewith to close the passage and to close either the passage or the outlet independently of 100 the signal.

9. An exhaust and signal control, comprising an exhaust muffler consisting of a central perforated open pipe, a concentric perforate cylinder thereon, an outer concentric shell around the cylinder, having a single discharge outlet of less capacity than the pipe apertures and the cylinder orifices, a blast signal, and controlling means for the outlet passage, adapted to operate the signal. 110

10. An exhaust and signal control, comprising an exhaust muffler, consisting of a series of concentric, annular compression chambers, having a central, direct exhaust passage, and a single restricted indirect discharge outlet from the outer chamber, signaling means adapted to be operated by the discharge from the outlet, and a signal controlling means for the passage, outlet and signaling means.

11. An exhaust and signal control, comprising an exhaust muffler consisting of a series of concentric, annular compression chambers, having a central, direct exhaust passage, and a single restricted indirect dis- 130

- charge outlet from the outer chamber, signaling means adapted to be operated by the discharge from the outlet, and a single controlling means for the passage, outlet and 5 signaling means integral with the muffler and the signaling means.
12. An exhaust and signal control, comprising an exhaust muffler consisting of a plurality of concentric, compression cylinders connected by reduction openings, a controlling valve casing forming a muffler head for the cylinders, a passage from the intake cylinder into the casing, an outlet from the discharge cylinder into the casing, a common 10 discharge from the casing, a blast signal on the casing, and a closure in the casing adapted to close the passage and simultaneously to operatively connect the outlet with the signal, and to close the passage or the outlet in 15 independently of the signal.
13. An exhaust and signal control, comprising an exhaust muffler consisting of an inner open, perforate pipe, a perforate cylinder concentric with the pipe, an outer imperforate cylindrical shell concentric with the cylinder, a valve casing forming a muffler head for the pipe and shell, a passage from the pipe end into the casing, a single restricted outlet from the shell into the casing, 20 a blast signal on the casing, a blast duct from the casing to the signal, a common discharge from the casing and a valve closure adapted to connect the discharge with either the outlet or the passage, or the outlet with 25 the blast duct.
14. An exhaust and signal control, comprising a central, open tube perforated between its ends, a sheet metal cylinder concentrically secured around the perforated portion, having sheet metal heads provided with inrolled, rounded integral marginal flanges, interlocking with corresponding peripheral grooves in the body, secured by lock nuts on the pipe, an outer sheet metal imperforate 40 shell concentric with the cylinder, a restricted outlet therefrom, a blast signal, and means controlling the outlet and the pipe, discharge end, adapted to turn the discharge from the 45 outlet through the signal.
15. In an exhaust muffler and signal control, having multiple reduction or compression chambers, provided with a direct passage and a single restricted outlet, a valve casing having a muffler head integral thereon 50 common to the initial and final chambers, a blast signal whose sounding bell is secured on the casing and whose blast duct and deflec- 55
- tor are integral with the casing, a discharge outlet into the casing from the final chamber, a port from the passage, a common discharge 60 from the casing, and a single closure adapted to connect either the port or the outlet with the discharge, or the outlet with the blast duct.
16. An exhaust and signal control comprising a cylindrical exhaust muffler, a combined muffler head and valve casing therein, having a direct exhaust passage and indirect outlet from the muffler and a common discharge, a blast duct and deflector integral 70 with the casing, a signal sounding bell secured on the casing in longitudinal alignment with the muffler, and a single closure rotatable in the casing, adapted to connect the outlet either with the common discharge 75 or the blast duct, or the direct passage with the common discharge.
17. An exhaust and signal control comprising a cylindrical exhaust muffler, a combined muffler head and valve casing therein, having a direct exhaust passage and indirect outlet from the muffler and a common discharge, a blast duct and deflector integral 80 with the casing, a signal sounding bell secured on the casing, in longitudinal alignment with the muffler, and a ported cylindrical closure in the casing, rotatably transverse to the muffler in the casing, adapted to connect the outlet either with the common discharge 85 or the blast duct, or the direct passage with the common discharge.
18. An exhaust and signal comprising a cylindrical exhaust muffler, a valve casing, a circular muffler head integral thereon closing one end of the muffler, provided with a direct 90 exhaust passage and an indirect outlet, a sounding bell secured on the casing in axial alignment with the muffler, a blast duct and deflector for the bell integral with the casing, a ported cylindrical closure held in yielding, 95 rotatably engagement with a counterbored valve seat in the casing, transverse to the muffler axis, and adapted to connect the outlet either with the blast duct or with a discharge opening in the casing or to connect 100 the passage with the discharge and an operating lever for the closure.

In testimony whereof I affix my signature in presence of two witnesses.
